UNITED STATES PATENT OFFICE.

ROLLAND W. TISCH, OF GRAND RAPIDS, MICHIGAN.

BIRD HOUSE.

Application filed June 5, 1926. Serial No. 113,880.

The present invention relates to bird houses; and its object is to provide a structure of that character improved in respects hereinafter appearing; and more particularly, to provide such a structure having interior parts which may be readily removed for cleaning, or other purposes.

This object is attained by, and the invention finds preferable embodiment in, the structure hereinafter particularly described in the body of this specification and illustrated by the accompanying drawings, in which:

Figure 1 is an end view of a bird house structure;

Figure 2 is a right-hand side view thereof, shown partially in central vertical longitudinal section taken on line 2—2 of Figure 1;

Figure 3 is a transverse vertical sectional view of the same taken on line 3—3 of Figure 2;

Figure 4 is an end view of the lower portion of the same, showing a modified means of support;

Figure 5 is a view in perspective of a removable vertical partition of said structure; and

Figure 6 is a view in perspective of removable connected horizontal partitions of the same.

In the accompanying drawings a bird box is shown in the form of a rectangular box, two opposite corners of whose ends 1, 1 are disposed vertically and the other two corners horizontally. The bottom of this box comprises relatively inclined portions 2, 2 extending outwardly-upwardly, and the top, open at 3 at one side, comprises a fixed roof portion 4 extending downwardly-outwardly and a closure portion 10 hinged at 5 to the roof portion and inclined relatively thereto downwardly-outwardly and adapted to close the opening 3.

Removably carried in the box is a centrally disposed vertical partition 6 removable through the open portion 3 of the top when the closure portion 10 is open as shown in Figure 3, and held in vertical position in the box by a pair of connected horizontal partition elements designated generally 7, 7 and extending between the ends 1, 1 respectively of the box and the vertical partition 6. Each of said pair of horizontal partition elements 7 is removable through the opening 3, and comprises partitions 8, 9 connected

and spaced apart vertically by vertical partitions 11. Each of said pair 7, 7 is held in horizontal position in the box by the portions 2, 2 of its bottom and the fixed portion 4 and the shut closure 10 comprising the top of the box, these parts engaging the opposite side edges 12, 12 of the partitions 8, 9.

Each end 1 of the box has openings or doors for the passage of the birds into and out of the box, these doors being arranged at different levels, the door 13 affording access to the chamber 14 in the upper part of the box, the door 15 affording access to the chamber 16 in its bottom part, and the doors 17, 18, 19 to the chambers 20, 21, 22 in its middle portion. It will be seen that when the closure is open, all these partitions may be readily removed for cleaning.

A flexible strip 23 may be included as a part of the hinged mounting of the closure, which may be held shut by latches 24. The box may be supported on a post 25 by a suitable connection, as that shown at 26, or 27.

The invention being intended to be pointed out in the claims, is not to be limited to or by details of construction of the particular embodiment thereof illustrated by the drawings or hereinbefore described.

I claim:

1. In a structure of the character described: a box having a bottom comprising relatively inclined portions extending outwardly-upwardly, opposite ends, and a top closure; a partition held in horizontal position in the box between the bottom and the shut closure and resting at its lateral edges on said portions respectively and removable from the box in the open position of the closure, an end of the box having openings above and below the partition.

2. In a structure of the character described: a box having a bottom comprising relatively inclined portions extending outwardly-upwardly, opposite ends, and a top closure; vertically spaced connected partitions held in horizontal position in the box between and in contact with the bottom and the shut closure and removable from the box in the open position of the closure, an end of the box having openings above and below the partitions.

3. In a structure of the character described: a box having a bottom comprising relatively inclined portions extending outwardly-upwardly, opposite ends, and a top

- closure; a removable vertical partition in the box; partitions on the opposite sides of said partition, holding the same in vertical position and held in horizontal position in the box between the bottom and the shut closure and removable from the box in the open position of the closure, the ends of the box having openings above and below the second-mentioned partitions.
- 10 4. In a structure of the character described: a rectangular box having a bottom comprising relatively inclined portions extending outwardly-upwardly, vertically-extending ends, and a top comprising a roof portion extending downwardly-outwardly 15 and a closure portion inclined relatively thereto and extending outwardly-downwardly; a partition held in horizontal position in the box between the bottom and the shut closure and removable from the box 20 in the open position of the closure, an end of the box having openings above and below the partition.

In testimony whereof I have hereunto set my hand at Grand Rapids, Michigan, this 24th day of May, 1926.

ROLLAND W. TISCH.
